UNITED STATES PATENT OFFICE

159,200

OIL BURNER

Herman O. Grimmeisen, West Springfield, Mass., assignor to Gilbert & Barker Manufacturing Company, West Springfield, Mass., a corporation of Massachusetts

Application August 9, 1949, Serial No. 4,368
Term of patent 14 years

(Cl. D81—2)

To all whom it may concern:

Be it known that I, Herman O. Grimmeisen, a citizen of the United States residing at West Springfield, Commonwealth of Massachusetts, have invented a new, original, and ornamental Design for Oil Burner, of which the following is a specification, reference being had to the accompanying drawing, forming a part hereof.

Referring to the drawing:

Fig. 1 is a rear elevational view of an oil burner embodying my new design;

Fig. 2 is an end elevational view thereof;

Fig. 3 is a front elevational view of the burner;

Fig. 4 is a top plan view thereof; and

Fig. 5 is a sectional view taken on the line 5—5 of Fig. 1.

The characteristic features of my design reside in the portions shown in full lines.

I claim:

The ornamental design for an oil burner, substantially as shown and described.

HERMAN O. GRIMMEISEN.
